UNITED STATES PATENT OFFICE.

AMOS H. SMITH, OF BROOKLYN, NEW YORK, ASSIGNOR TO AMERICAN BANK NOTE COMPANY, OF NEW YORK, N. Y., A CORPORATION OF NEW YORK.

NUMBERING HEAD.

Application filed June 16, 1922, Serial No. 568,734. Renewed September 25, 1923.

To all whom it may concern:

Be it known that I, Amos H. SMITH, a citizen of the United States, residing at the borough of Brooklyn, in the city of New 5 York, county of Kings, and State of New York, have invented certain new and useful Improvements in Numbering Heads, of which the following is a specification, reference being had therein to the accompanying 10 drawings, which form a part thereof.

My invention relates to numbering heads, and more particularly to a type of numbering head which is positively actuated, wherein the transfer mechanism between the 15 respective digit wheels is so constructed as to ensure the timely progressive actuation of digit wheels of higher denomination.

A numbering head embodying my invention is so constructed as to be actuated by 20 means independent of the impression cylinder of a numbering machine with which the head is used, the actuating mechanism being operative upon the units wheel in a manner to impart rotation thereto as a result of engagement of the actuating member with a 25 striker member. The actuating member has an oscillatory movement, thus avoiding any possibility of overrunning of the units digit wheel, or any wheel of higher denomination. 30 The necessity of providing in the head, any springs which are relied upon to effect the turning of the digit wheels, is also avoided, thus reducing to a minimum likelihood of the head becoming inoperative as a result of 35 the breakage of such springs. This condition is desirable, since when spring actuated numbering heads are employed, the resistance encountered by the spring in setting the head becomes progressively greater with a 40 continued run of the head.

A numbering head embodying my invention is so constructed that the various parts thereof may have sufficient material therein to minimize wear, the relation of the various 45 parts being such as to permit the digit wheels to be set closely together and to be acted upon by a detent pawl operating in a manner to permit free rotation of the various digit wheels while preventing a partial accidental turning of any wheel sufficient to result in a skipping of the numbers or a loss in alinement.

In a numbering head embodying my invention, I provide a special actuating mechanism by means of which the rotative move-

ment of the units digit wheel may be secured without absolute precision work in parts of the head, slight lost motion or looseness from wear being permissible by reason of the manner of combining and constructing the various parts, without any loss in the accuracy in the functioning of the head.

The transfer mechanism forming a part of the head is so constructed and arranged that there can be no multiplication of slight error, thus permitting a long run of a head without any material deviation from the original alinement of the printing characteristics upon the various digit wheels.

The invention consists primarily in a numbering head embodying therein a sequence of digit wheels each having a plurality of gear teeth thereon, the top of each of said teeth being formed as a printing surface, said wheels being independently rotatable 70 about a common axis, and means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, and having one of the 75 teeth laterally extended to engage the teeth of a digit wheel of next higher denomination, a ratchet wheel carried by the units digit wheel, a spring-pressed pawl co-operating with said ratchet wheel, an oscillatory member adapted to be engaged by a striker member, and operative connections between said oscillatory member and said pawl; and in such other novel features of construction 80 and combination of parts as are hereinafter 85 set forth and described, and more particularly pointed out in the claims hereto appended.

Referring to the drawings,

Fig. 1 is a plan view of a numbering head 100 embodying my invention;

Fig. 2 is a side view thereof;

Fig. 3 is an end view from the right of Fig. 1; and

Fig. 4 is a section on the line 4—4 of 105 Fig. 1.

Like numerals refer to like parts throughout the several views.

In the embodiment of my invention shown in the drawings, the main frame of the ma- 110

chine is shown at 10, said frame being provided with a fixed shaft 11 upon which are idly mounted in close juxtaposition, a sequence of independently rotatable digit 5 wheels 12, 13, 14, 15, 16, 17, 18 and 19, each of which is identical in construction so as to require a detailed description of but one of these wheels, as the units wheel 12. Said units wheel, however, differs from the other 10 wheels in the respect that a part of the main actuating means for the numbering head is carried thereby. Said digit wheel has, about the periphery thereof, a sequence of ten long gear teeth 20, the top of each of said teeth 15 being formed as a printing surface 21, said printing surfaces having successively the digits 0 to 9 thereon, in cameo type.

Upon one side of the digit wheel is a detent and alining wheel 22 having a sequence of triangular notches therein indicated at 23. Associated with each of said wheels 22 is a detent and alinement pawl 24 having a wedge-shaped tooth 25 conforming in contour with the notches 23 so that 25 said pawl in addition to holding its digit wheel against rotation, will have a wedging and centering action thereon which will assure a proper alinement of the various printing characters thereon with the characters upon adjacent digit wheels, even though there is an absence of precise accuracy in the actuating mechanism. This alinement, as will more fully appear hereinafter, is assisted by the construction of 30 transfer mechanism used.

The various pawls 24 are idly mounted upon a shaft 26 extending transversely of the head, said pawls respectively being provided with a projecting heel 27 acted upon 40 by a suitable spring 28, this spring in the form of the invention shown being a coiled spring positioned in a spring cup 29 formed in the frame 10 of the machine.

Each of the digit wheels 13 to 19 contains 45 teeth similar to the teeth 20 of the wheel 12 and each have similar printing surfaces 21 thereon. Each of said digit wheels also carries a detent and alining notched wheel 22 with its spaced notches 23 corresponding in 50 number with the teeth 20, and coacting with a detent and alinement pawl similar to the pawl 24.

It will be observed from the foregoing that each of the digit wheels 12 to 19 has 55 rotary movement about a common axis and that said wheels are progressively actuated from a single main actuating mechanism through the medium of a transfer mechanism deriving its power from the main actuating means which operates only upon the units digit wheel. While I have referred to the power being applied to the units digit wheel it must be borne in mind that in all numbering heads the digits are so positioned thereon that the head may either be actuated

with a progressively increasing total or with a progressively decreasing total, according to the arrangement of the numbers upon the digit wheels.

Also carried by the frame 10 is a shaft 30 counter to the shaft 11, which shaft has idly mounted thereon a sequence of transfer wheels 31, 32, 33, 34, 35, 36 and 37 associated and co-operating with the digit wheels 12 to 19 respectively. Each of the transfer 75 wheels 31 to 37 is identical in construction and arrangement of parts with every other, with the exception that by reason of the greater wear upon the wheel 31, this wheel is made of heavier construction. 80

Each of the transfer wheels 31 to 37 is provided with a sequence of teeth corresponding in number, and adapted to co-operate with the gear teeth 20 upon the digit wheel with which it is associated and from 85 which it derives its power, these teeth being so formed as to prevent rubbing contact between the printing surface upon its digit wheel and the bottom of the recess between the succeeding teeth upon the transfer wheel. 90

Each of the wheels 31 to 37 has nine narrow teeth, the tenth tooth being relatively wider so as to be adapted to engage the gear tooth upon the wheel of next higher denomination. In this manner progressive 95 actuation of the successive digit wheels is assured and continuous engagement of each transfer wheel with its associated digit wheel is assured.

Idly mounted upon the shaft 11 is a 100 forked swing frame 38 having pivoted therein a pawl 39 acted upon by a spring 40, said pawl being adapted to co-operate with a ratchet wheel 41 having ten teeth carried by the units digit wheel 12 and rotating 105 therewith.

Also idly mounted upon said shaft 11 outside of the main frame 10 of the machine, is an oscillatory arm 42 having a crank carrying an anti-friction roller 43 adapted to be engaged by the striker member of a numbering machine. The said arm 42 is acted upon by a torsion spring 44, the sole function of which is to restore the arm 42 to its normal position, this spring having no function whatever in imparting movement to the digit wheels, and being at all times subject to uniform stresses of a character which will minimize likelihood of breakage of the spring. The oscillatory member or arm 42 is operatively connected with the pawl 39 through the medium of said swing frame 38 and a stud 45 carried by said arm 42 and passing through a segmental slot 46 in the side of the main frame 10 and entering a 115 fork of said swing arm. 120

The various transfer wheels are so set with relation to their respective digit wheels, that the long tooth thereof will operatively engage or mesh with the teeth of 130

the digit wheel of next higher denomination only when the digit 9 of the digit wheel with which this transfer wheel is associated, is in the printing position.

5 The operation of the herein described mechanism is substantially as follows:—

In the accompanying drawings, the numbering head is shown at approximately four times its actual size, in order to clearly bring 10 out the different structural characteristics of the invention.

It will be observed that each of the digit wheels may be turned entirely independently of any other digit wheel for the purpose of setting the head, so long as in so setting the head a digit 9 is not brought into and moved out of the printing position so as to actuate the transfer mechanism operative upon the next wheel. If it be desired to set all the digit wheels at 0, this 15 is accomplished by setting all of the wheels with the digit 9 in the printing position and then actuating the units digit wheel, thus simultaneously moving all of the wheels 20 one-tenth of a revolution.

All of the digit wheels, excepting the units digit wheel, may be turned in either direction when setting the head.

When the head has once been set, the 30 various digit wheels 13 to 19 will be progressively actuated either with ascending or descending totals, according to how the digits are arranged upon the various wheels.

The actuating power is applied directly 35 to the units wheel 12, the transfer wheel 31 turning with the wheel 12, the long tooth of said transfer wheel engaging a tooth 20 of the digit wheel 13 each time the digit 9 of the units wheel 12 comes to the printing 40 position, so that upon the next actuation of the units wheel, the tens wheel 13 will receive one-tenth of a revolution before the long tooth of the transfer wheel 31 passes out of mesh with the tooth 20 of the digit wheel 13. This operation of transfer is carried on 45 progressively with each of the digit wheels 13 to 19 and transfer wheels 32 to 37.

Numbering heads of the type to which my 50 invention relates, are mounted upon a numbering machine, the ordinary arrangement being to use them in spaced groups. This numbering machine is provided with striker members adapted to engage the roller 43 carried by the arm 42 of the various heads at 55 least once during each revolution of the cylinder carrying the numbering heads, the result of the engagement being the oscillation of the arm 42, which through the stud 45 engaging the forks of the swing frame 38, 60 will rock said swing frame, thus causing a one-tenth revolution of the units digit wheel through the pawl 39 and the ratchet wheel 41, which latter is carried by the units wheel.

65 In this manner the actual turning power

is applied directly to the units wheel, the torsion spring 44 being provided merely for the purpose of returning the arm 42 and the swing frame 38 to their normal position after the head has passed the striker member. 70

By employing the notched wheel 22, and the triangular head 25 upon the alining and detent pawl 24, said pawl will be caused to ride out of engagement with the notch 23 to permit the turning of the units digit wheel 75 and will engage the succeeding notch 23 in the wheel 22 as the digit wheel is approaching the limit of its turning movement under the control of the swing frame 38 and pawl 39. If the feeding movement under the control of the pawl 39 is not exactly one-tenth of the circumference of the digit wheel, or 80 36° in arc, this pawl 24 will either advance or return the digit wheel sufficiently to always ensure the exact positioning of the printing surface 21 upon the top of any tooth 20. This condition is possible since this pawl 24 is the only mechanism acting upon each digit wheel which places any 85 limitation upon the free turning movement 90 of the wheel.

By reason of the above condition there can be no accumulation of error throughout the sequence of digit wheels 12 to 19, and a 95 necessity for any great nicety in the production of the main actuating means and the transfer wheels is avoided since if there be any error in these parts it will be corrected by the pawl 24 and the notched wheel 22 associated with and carried by each digit 100 wheel immediately following the actuation of that digit wheel.

The transfer wheels 31 to 37 associated with the digit wheels 12 to 19 respectively turn with their respective digit wheels, but 105 have no operative effect until the digit 9 of the digit wheel applying power to the transfer wheel, is in the printing position, the next actuation of said digit wheel, however, causing the wheel of next higher denomination 110 to be actuated through the transfer wheel.

Except for the transfer mechanism, each digit wheel functions entirely independently of every other digit wheel, likelihood of an 115 accidental actuation of a wheel of higher denomination by a wheel of lower denomination because of the accumulation of ink between said wheels, being practically impossible, since the power required to disengage 120 the pawl 24 from a notch in the wheel 22 is greater than the strength of any bond or adhesion due to the presence of ink between the digit wheels.

The deep space between the teeth of the 125 transfer wheels 31 to 37, as indicated more particularly in Fig. 4 of the drawings, will prevent any such rubbing contact between the printing surfaces 21 and the transfer wheels as might interfere with a proper ink- 130

ing of said printing surfaces, although ordinarily said surfaces will be inked after the digit wheels have been actuated.

- Any wear on the forked frame 38, stud 45, 5 roller 43, ratchet wheel 41 and pawl 39 will be compensated for by the pawl 24 and the wheel 22 since no amount of wear could occur in such parts as would so limit the action of the units digit wheel as to prevent 10 the functioning of said pawl 24 when correcting any short or excess movement of the units wheel. Exactitude in the movement of the units wheel will ensure sufficient exactitude in the movement of all of the other 15 digit wheels through the transfer wheels 31 to 37, to ensure the pawl 24 operative upon each of said other wheels accurately positioning said other wheels.

It will be observed that movement of the 20 arm 42 of the main actuating mechanism of the numbering head, causes the turning of the units digit wheel when and as power is applied to said arm by the co-operating striker member of the numbering head, so that said 25 actuating means will always work under exactly the same conditions irrespective of the number of wheels which have to be turned with any actuation thereof; and that the actuation of the various digit wheels is 30 not dependent in any way upon springs which are subject to breakage, particularly when a machine is running at high speed.

The torsion spring 44 need be of merely 35 sufficient strength to move the load of the arm 42, roller 43, stud 45, swing frame 38 and pawl 39, which load upon said spring is constant so that breakage of the spring is so remote a contingency as to be no factor in the production of the numbering head.

40 It will be observed that each of the digit wheels 12 to 19 is normally restrained by the alining and detent pawl 24 co-operating therewith, which pawl in this respect acts as a locking member normally engaging its co- 45 operating member carried by its digit wheel, and movable out of the locking relation only as a result of movement of this member which is coincident with that of the wheel itself. The effectiveness of this locking 50 means results from the fact that considerable movement against gradually increasing resistance is required to turn any wheel, and that this resistance is sufficiently great to require a positive application of power greater 55 than the binding action of foreign substances which may enter between succeeding wheels.

It will also be noted that the swing frame 60 38 and its pawl 39 acts directly upon the ratchet wheel 41 carried by the units wheel, and that there is no possibility of a loss of alinement as a result of accumulated error since there are no gear trains, the various gears of which are constantly in mesh, and correction of any error is secured after 65 each actuation of each wheel. In fact no

two digit wheels are operatively connected except during that interval when the long tooth of one of the transfer wheels 31 to 37 is actually operative in imparting movement to a wheel of next higher denomination, said 70 wheels being entirely independent one of the other at all other times.

It is not my intention to limit the invention to the precise details of construction shown in the drawings, it being apparent that such may be varied without departing from the spirit and scope of the invention.

Having described the invention, what I claim as new and desire to have protected by Letters Patent, is:—

1. A numbering head embodying therein a sequence of digit wheels each having a plurality of gear teeth thereon, the top of each of said teeth being formed as a printing surface, said wheels being independently rotatable about a common axis, and means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, and having one of the teeth laterally extended to engage the teeth of a digit wheel of next higher denomination, a ratchet wheel carried by the units digit wheel, a spring-pressed pawl co-operating with said ratchet wheel, an oscillatory member adapted to be engaged by a striker member, and operative connections between said oscillatory member and said pawl.

2. A numbering head embodying therein a sequence of digit wheels each having a plurality of gear teeth thereon, the top of each of said teeth being formed as a printing surface, said wheels being independently rotatable about a common axis, and means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, and having one of the teeth laterally extended to engage the teeth of a digit wheel of next higher denomination, a ratchet wheel carried by the units digit wheel, a swing frame rotatable about an axis coincident with that of said digit, a spring-pressed pawl carried thereby and co-operating with said ratchet wheel, an oscillatory member adapted to be engaged by a striker member, connections between said oscillatory member and said swing frame, and means for restoring said 120 swing frame, and means for

member, said frame and said pawl to normal after each actuation of the units digit wheel.

3. A numbering head embodying therein a sequence of digit wheels each having a plurality of gear teeth thereon, the top of each of said teeth being formed as a printing surface, said wheels being independently rotatable about a common axis, and means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, and having one of the teeth laterally extended to engage the teeth of a digit wheel of next higher denomination, a ratchet wheel carried by the units digit wheel, a forked swing frame movable about an axis coincident with that of said digit wheel, a spring-pressed pawl co-operating with said ratchet wheel and carried by said frame, an oscillatory member adapted to be engaged by a striker member, a stud carried by said oscillatory member and entering the fork of said swing frame, and means for restoring said member, said frame and said pawl to normal after each actuation of the units digit wheel.

4. A numbering head embodying therein a sequence of digit wheels each having a plurality of gear teeth thereon, the top of each of said teeth being formed as a printing surface, said wheels being independently rotatable about a common axis, and means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, and having one of the teeth laterally extended to engage the teeth of a digit wheel of next higher denomination, a ratchet wheel carried by the units digit wheel, a forked swing frame movable about an axis coincident with that of said digit wheel, a spring-pressed pawl co-operating with said ratchet wheel and carried by said frame, an oscillatory member adapted to be engaged by a striker member, a stud carried by said oscillatory member and entering the fork of said swing frame, and a torsion spring operative upon said oscillatory member and adapted to restore said member, said swing frame and said pawl to normal after each actuation of the units digit wheel.

5. A numbering head embodying therein a sequence of digit wheels each having a

plurality of gear teeth thereon, the top of each of said teeth being formed as a printing surface, and said wheels being rotatable about a common axis, a detent and alining wheel having a sequence of substantially triangular notches therein carried by each of said digit wheels, a spring-pressed detent and alining pawl associated with each of said detent and alining wheels and having a wedge-shaped tooth conforming to the notches in said wheel, and means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, and having one of its teeth laterally extended to engage the teeth of the digit wheel of next higher denomination, and a main actuating mechanism operative upon the units digit wheel and upon the wheels of higher denomination and through said transfer wheel.

6. A numbering head embodying therein a sequence of digit wheels each having a plurality of gear teeth thereon, the top of each of said teeth being formed as a printing surface, and said wheels being rotatable about a common axis, a detent and alining wheel having a sequence of substantially triangular notches therein carried by each of said digit wheels, a spring-pressed detent and alining pawl associated with each of said detent and alining wheels and having a wedge-shaped tooth conforming to the notches in said wheel, and means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, and having one of its teeth laterally extended to engage the teeth of the digit wheel of next higher denomination, a ratchet wheel carried by the units digit wheel, a spring-pressed pawl co-operating with said ratchet wheel, an oscillatory member adapted to be engaged by a striker member, and operative connections between said oscillatory member and said pawl.

7. A numbering head embodying therein a sequence of digit wheels each having a plurality of gear teeth thereon, the top of each of said teeth being formed as a printing surface, and said wheels being rotatable about a common axis, a detent and alining wheel having a sequence of substantially triangular notches therein carried by each

of said digit wheels, a spring-pressed detent and alining pawl associated with each of said detent and alining wheels and having a wedge-shaped tooth conforming to the notches in said wheel, and means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, and having one of its teeth laterally extended to engage the teeth of the digit wheel of next higher denomination, a ratchet wheel carried by the units digit wheel, a forked swing frame movable about an axis coincident

with that of said digit wheel, a spring-pressed pawl co-operating with said ratchet wheel and carried by said frame, an oscillatory member adapted to be engaged by a striker member, a stud carried by said oscillatory member and entering the fork of said swing frame, and a torsion spring operative upon said oscillatory member and adapted to restore said member, said swing frame and said pawl to normal after each actuation of the units digit wheel. 20

In witness whereof I have hereunto affixed my signature, in the presence of two subscribing witnesses, this 14th day of June, 1922.

AMOS H. SMITH.
